PROTECTIVE DEVICE FOR FILM PROJECTING APPARATUS

Filed July 14, 1930

UNITED STATES PATENT OFFICE

LUDWIG OHR, OF WORMS, GERMANY

PROTECTIVE DEVICE FOR FILM PROJECTING APPARATUS

Application filed July 14, 1930, Serial No. 467,712, and in Germany February 21, 1929.

My invention relates to a novel and simple protective device, by means of which film strips are prevented from becoming ignited when tearing or dwelling within the path of the light rays a longer time than admissible. Besides securing this general object, there is a highly important object of my invention to obtain a steady and continuous movement of the film band free from vibrations, thus the 10 result of my invention extending on two different directions of high importance. Hitherto, one has well been successful when using centrifugal devices, which my invention, too, employs, in operating reasonably the safety 15 flaps, closing the image-window of the apparatus, but nobody has been successful in getting a steady, continuous run of the film band. When using such safety means, this is due to the discontinuous motion of the film 20 itself, which is used, by means of a governing member viz. a roller and transmitting elements, to operate the centrifugal device; these means undergoing to the action of inertia 25 transmit inversely their discontinuous movement to the film band and cause it to run in a vibrating manner.

My invention, therefore, consists in such a combination of the known centrifugal device with other elements in a distinct arrangement 30 that the drawbacks above mentioned are removed.

To make my invention more clear and to give full, easy understanding of it, drawings are annexed, in which Fig. 1 is a back elevation of the necessary parts of the projecting apparatus in connection with the new driving means for the safety contrivance, Fig. 2 a corresponding side view, Fig. 3 the same view dispensable details being omitted, Fig. 40 4 a front view seen in the direction of the arrow α and Fig. 5 a vertical section of the centrifugal device in a larger scale.

r designates the known frame of a safety flap for the image window, through which the condenser rays are passing; the window w^1 is cut out from the wall w of the projecting apparatus not further shown. Between frame r and wall w passes through the film strip not further shown along the window w^1 in the usual manner. By means of screw bolts

r^1 on the frame r a bracket m is fixed on which the centrifugal device, the means for governing the door k and the gear for the former are mounted. At the top end of the bracket m , by means of eyes m^1 , the rotating shaft p rests, upon which the hollow roller a is freely mounted. For connecting the members p and a the helical spring l serves which is fixed at a^1 to the hollow roller a and at p^1 to the shaft p . Furthermore, with the teeth a^2 of the roller a a guiding roller b cooperates in the usual manner tightened by a flat spring b^1 . By the eyes m^2 at one end of the bracket the centrifugal device is mounted, which consists of a swinging ring g pivotally carried by means of pointed pivots from a shaft f . The centrifugal ring g is, by means of a slight ring member h^1 , fastened to a governing sleeve h , sliding along the shaft f and governing a slight transmission lever i , pivotally arranged at i^1 on the wall w and connected at i^2 to the safety door k .

To transmit the rotation of the governing roller a to the centrifugal shaft f two gear wheels are provided for, a small one fixed on the shaft f and a large one d attached to a bearing disk d' freely mounted with its hub d^2 on the governing shaft p and also fixed to the latter by means of a helical spring s .

The action is as follows. In its normal run the film operates the roller a , but not in a rigid manner, as hitherto, but in an elastic way, thus all shocks otherwise transmitted to the roller and inversely by the latter again to the film band, are received and neutralized by the connecting spring l . This neutralization is increased by the additional spring s , taking along the intermediate disk d^1 thus rapid rotation of the gear wheels d , e and further of the centrifugal shaft f are obtained. Accordingly, the swinging ring g puts in upright position and the governing sleeve h is drawn to the lefthand side, see arrow α , Fig. 5. Due to this, the lever i opens the window k and holds it open. The film strip preserving a perfectly continuous motion, the safety flap k rests open as long as the centrifugal ring rotates rapidly. If, however, the run of the film and according-

ly the rotative motion of the roller *a* are disturbed the centrifugal power ceases to act upon the ring *g* and by gravity the door is closed immediately.

5 I wish to be understood that my invention is not exhausted by the special construction and arrangement as illustrated, but it comprises in general the technical idea of inserting one or several elastic means for coupling 10 the governing roller *a* or some equivalent member and transmitting the gear for the centrifugal device, to secure by this way the steady and continuous projecting of the film.

What I claim is:

15 1. A protective device for film projecting apparatus, comprising in combination with a protective door, a swinging ring and a rotatable shaft, a hollow roller operated by the film, a gearing shaft, a helical spring, mounted 20 within the hollow roller resiliently connecting the gearing shaft with the hollow roller, transmitting means operated by the gearing shaft and turning the rotatable shaft, a transmitting member connected with the 25 swinging ring and freely sliding on the rotatable shaft, a lever operated on its one end by the transmitting member and acting on the other end upon the protective door.

2. A protective device for film projecting 30 apparatus, comprising in combination with a protective door, a swinging ring and a rotatable shaft, a hollow roller and a counter roller resiliently mounted, the film passing through between them, a gearing shaft, a 35 helical spring mounted within said hollow roller and attached on its one end with it and its other end with the gearing shaft, a bearing disk freely mounted on the gearing shaft, a connecting spring joining the bearing disk to the gearing shaft, a toothed wheel 40 fixed to the bearing disk, a toothed wheel fixed to the rotatable shaft, a coupling sleeve slidably mounted on the rotatable shaft and attached to the swinging ring, a lever arrangement 45 on the one hand attached to the coupling sleeve and on the other hand to the protective door.

3. A protective device for film projecting apparatus, comprising in combination 50 with a protective door and a centrifugal device, a roller and a counter roller both operated by the film, a gearing shaft, resilient means connecting the gearing shaft to the roller, transmitting means including a resilient connection for transmitting the motion 55 of the gearing shaft to the centrifugal device, a lever arrangement for governing the protective door and means for transmitting the motion of the centrifugal device to 60 said lever arrangement.

4. A protective means for film projecting apparatus, comprising in combination a door, a roller over which the film passes, a shaft on which the roller is mounted, a second shaft, a centrifugal device mounted on the

second mentioned shaft, gearing between the two shafts, a resilient connection between the first mentioned shaft and the roller, and a lever between the centrifugal device and the door, whereby when the centrifugal device is operated, the door will be opened. 70

5. A protective means for film projecting apparatus, comprising in combination a door, a shaft, a ring-like element mounted to tilt on the shaft, a sliding collar on the 75 shaft, a flexible connection between the collar and ring, a roller over which the film passes, gearing between the roller and shaft, and a connection between the collar and door, whereby upon rotation of the roller the ring 80 is tilted by centrifugal force and the door is opened.

6. A protective means for film projecting apparatus, comprising in combination a door, a shaft, a roller mounted on the shaft, a resilient connection between the shaft and roller, a second shaft parallel with the first mentioned shaft, a centrifugal device mounted on the second mentioned shaft, gearing between the two shafts, a resilient connection 90 between the gearing and the first mentioned shaft, and a connection between the centrifugal device and the door.

7. A protective means for film projecting apparatus, comprising a door, a shaft, a 95 tilttable ring mounted on the shaft, a second shaft, a hollow roller mounted on the second mentioned shaft, a spring mounted in the hollow roller and connecting the latter with the shaft, means for transmitting motion 100 from the second mentioned to the first mentioned shaft, a sliding element mounted on the first mentioned shaft and flexibly connected to the tilttable ring, and a pivotal connection between the door and the sliding 105 element.

In testimony whereof I affix my signature.
LUDWIG OHR.
